UNITED STATES PATENT OFFICE.

THOMAS N. COFFELDER, OF PITTSBURGH, PENNSYLVANIA.

AUTOMATIC RAILWAY-CROSSING GATE.

Application filed November 27, 1926. Serial No. 151,119.

This invention relates to automatically operated railway gates which are operated by an engine or train of cars passing over the region of the railway guarded by the gate.

5 It is among the objects of this invention to provide an automatic railway crossing gate which shall be positively operated by the passing of trains over sections of the tracks remote from the crossing to close the 10 gate arms, and subsequently, after the trains have passed the crossing, the gates will be automatically opened by the same or similar operating mechanism.

Another object of this invention is to provide 15 a system for automatically operating gate arms for railway crossings by fluid pressure which shall embody a minimum number of operating parts of simple compact and durable mechanical construction 20 and which shall be effective in its operation of closing and opening the gate arms responsive to the passing of railway trains over rails of the tracks with which the operating mechanism is associated.

25 Other objects of this invention are to provide mechanism embodying a plurality of fluid pressure elements for respectively actuating the operating mechanism of the gate arms, for supplying an operating medium or fluid under pressure to the operating cylinder, and valve mechanism for selectively directing the operating medium to the top or bottom of the gate operating piston to raise or lower the gate arm and for returning 30 the operating medium to a supply tank from which it is conducted to the pressure supply member.

Various types of mechanism for automatically operating gate arms of railway crossings have been heretofore proposed which 40 commonly employ complicated gearing or complex electrical systems for operating the gate arms responsive to the operation of track instruments that are actuated by the 45 passing of railway vehicles over the tracks at some distance remote from the crossing at which the gates are located.

In accordance with the present invention 50 gearing and electrical elements are entirely dispensed with and the operating and actuating mechanism herein disclosed embodies a series of levers and fluid pressure actuated elements which are of simple construction and which are not so readily susceptible of 55 becoming worn or broken so as to interrupt

the function or successful operation of the system which is a very vital element in a gate operating mechanism in which safety is the principal consideration.

In the accompanying drawings constituting a part hereof and in which like reference characters designate like parts Fig. 1 is a diagrammatic view of an automatically operated railway crossing gate arm and operating mechanism therefor embodying the 60 principles of this invention; Fig. 2 is a top plan view of the gate arm and standard upon which it is mounted; Fig. 3 is a view partially in side elevation and partially in section of the arm and standard shown in 70 Fig. 2; Fig. 4 is a diagrammatic view of a railway track illustrating the track instruments, the pipe connections leading from the gate arm operating mechanism to the regulating valve, fluid supply tanks and pressure pumps all connected to be operated through 75 the track instruments when they are actuated by a vehicle passing over the rails; Figs. 5 to 11 inclusive are detail views of the valve mechanism of which Fig. 5 is a sectional view of a valve in one operative position; Fig. 6 a section on line VI—VI of Fig. 5; Fig. 7 a plan view of Fig. 5; Fig. 8 a plan view of a valve in another operative 80 position; Fig. 9 a section on line IX—IX of Fig. 5; Fig. 10 a section on line X—X of Fig. 5; and Fig. 11 a section, taken on line XI—XI of Fig. 6; Figs. 12 and 13 are vertical and longitudinal sectional views of the 85 pump elements employed in the pressure system; and Fig. 14 is a detail view of the valve regulating mechanism constituting a part of 90 the track instruments.

Referring to Figs. 1 to 3 of the drawings the construction therein illustrated comprises a vertical standard or pedestal member 1 having a gate arm 2 adapted for vertical swinging movement mounted thereon, the arm 2 being provided with hinges 3 opening outwardly to permit the escape of 95 vehicle or person that may be trapped on the track side of the arms when the gates are lowered. The arm 2 is carried by a shaft 4 which is connected by a bell crank 5 through the link 6 to an operating lever 7, this crank, link and lever constituting a toggle 100 connection. Link 6 is mounted in guide 8 and the free end of the lever 7 is disposed in a slotted opening 9 of a piston rod 10. The short end of the gate arm is provided 105

with counterweights 11 to provide a balanced lever, operating around the shaft 4 as a fulcrum member, which requires very little effort to unbalance it to raise or lower the gate arm.

A piston 12 connected to one end of the rod 10 operates in a cylinder 13 having cylinder heads 14 and 15 provided with ports 16, 17, 18 and 19 respectively. The piston member 12 is provided with oppositely acting check valves 20 and 20^a and the ports of the cylinder heads are opened or closed by a pair of teeter valves 21 and 22. The ports 16, 17, 18 and 19 are respectively connected by pipe lines 23, 24, 25 and 26 communicating with regulating valves 27 and 28.

Referring to Fig. 4 the valves 27 and 28 are connected by pipe lines 29 and 30 to storage tanks 31 and 32 respectively and by pipe lines 33 and 34 to pressure pumps 35 and 36 respectively.

Referring to Figs. 1, 4 and 14 similar track instruments located on each side of the gate consist of a pair of levers 39 and 40 respectively actuated by fingers 41 and 42, and 41^a and 42^a. As shown in Fig. 14 the fingers comprise lower and upper members 43 and 44 pivoted at 45, the members being respectively provided with lugs 46 and 47 which when engaged by movement of the member 44 in one direction constitute the members 43 and 44 a rigid lever pivoting at 45, the member 44 being movable about the pivot 45 in the opposite direction although normally biased to effect engagement of the lugs 46 and 47 by a spring 48. A connecting link 50 is connected at one end to one of the fingers of lever 39, and at the other end to a valve regulator arm 51 operating the valve 27; likewise a similar link 50^a is also connected to arm 51^a regulating valve 28.

The track instruments also embody a pair of rocker arms 53 and 53^a pivotally connected at 54 and 54^a to the rail, or in brackets mounted on the rail, and provided with levers 55 and 55^a connected to the ends of piston rods 56 and 56^a of the pumps 35 and 36 respectively.

The pumps are provided with check valves to cause one-way flow of the operating fluid from the tanks to the valves, and being similar in construction, their operation may be explained by reference to Figs. 12 and 13, illustrating pump 36. As here shown valve 57 is provided with a lower stop and 57' with an upper stop, which prevent the ball member from seating and closing those openings. The action is that as the piston rises, valve 57 closes and operating fluid is drawn in from the tank; similarly, when the piston descends, the fluid passes into pipe 34 but is prevented from entering 34 by closing of valve 57'.

Referring to Figs. 5 to 11 inclusive, the valve mechanism illustrated therein comprises a stationary valve cylinder or housing 60 having flanged ends 61 for receiving the end brackets 62 and 63, the latter being provided with ports or openings communicating with the pipe lines leading to the pumps, tanks and the operating cylinder of the gate arm. Within the cylinder or housing 60 is disposed a rotatable valve block 64 provided with a plurality of ports or openings 65 which are eight in number and interconnected as follows; two oppositely disposed ports 65 are connected by the channel 66; the two ports 65^a whose axis is perpendicular to that of 65, are connected by a channel 66^a; and two ports 65^b are connected by channel 66^b, and the two remaining ports 65^c by channel 66^c, in the manner apparent from Figs. 5, 7 and 9. The rotatable block 64 is provided with a shaft 67 extending through the end bracket 62 and a coil spring 68 is interposed between the members 62 and 64 to maintain the latter in its proper position. A crank arm 51 is secured to the end of the shaft 67 for subjecting the latter to angular movement when actuated by the linkage 50 connecting the arm with the lever and fingers 39, 41 and 42.

The operation of this device is briefly as follows:

Referring to the several figures of the drawings the two units comprising pumps, valves, storage tanks and track instruments are identical in construction and grouped in units or systems, spaced apart, and remote from the gate arm, the distance at which they are spaced being determined by the length and speed of trains passing over the tracks in the region of a particular automatic crossing gate installation. The longer the trains or the faster the speed of the trains the greater the distance will be at which these associated units are located.

With particular reference to Fig. 1 assuming a train to be passing in a direction extending from left to right the first wheel passing over the rails will initially strike the finger 41 which is designed to be rigid when pivoted in the direction indicated. The movement of the finger will effect a pull on the lever 39 which by virtue of its bell crank connection with the linkage 50 effects a movement of the lever 51 which rotates the valve block 64 causing the ports 65 to register with channel 66 connecting pipe 33 leading from the pump 35 and the pipe 25 leading from the operating cylinder 13 as shown by Fig. 7. In this position communication is also established between the pipe 23 leading from the upper head of the cylinder 13 and the pipe 29 of the storage tank 31 as shown in Figs. 5 and 7. As the wheels of the train pass over the rocker arm 53 the first wheel depresses the upraised arm, causing the de-

pressed arm to rise and this is in turn depressed by the next wheel; this action is continuous while the train is passing, and by this reciprocating motion the pump piston 56 is actuated to pump the operating medium or fluid from the storage tank 31 through the pipe line 33' into the bottom of the cylinder 13 underneath the piston 12 through the passage established by the pipe lines 23 and 25 and the ports of the valve member 27 communicating therewith. At the same time the valve 28 is in a position such that the ports connect pipe 24 with tank 32 through pipe 30 as seen in Fig. 8, this position resulting from the previous operation of this unit.

Referring to Fig. 3 it will be noted that as fluid under pressure passes into the cylinder 13 through the port 18 from the pipe line 25 as explained, the teeter valve 22 will function to close the port 19 to shut off communication with the pipe 26. The subsequent pumping action will cause the piston member 12 to rise in the cylinder 13 which by virtue of its toggle connection with the gate arm causes the latter to be lowered in the position shown in dotted lines in Fig. 1. While the piston is rising in the cylinder the fluid above the piston member will flow through both of the upper ports 16 and 17 through the pipe lines 23 and 24 through the valves 27 and 28 into the storage tanks 31 and 32. Continued operation of the pump after the piston has reached the limit of its upward travel will build up excess pressure behind the piston; this will be relieved by the valve 20, the excess fluid passing therethrough being returned to the tanks as before. As long as the train continues to pass over the first unit of track instruments the gate arm will remain in its horizontal or closed position and inasmuch as the finger 42 is arranged to be broken when it is tripped by the wheels passing in the direction which constitutes the finger 41 a rigid member the valve arm 51 will not be moved until a train has passed over the track in the opposite direction.

After the train has passed the crossing at which the gate arms are located it will strike the second unit of track instruments on the other side thereof which is arranged so that the finger 41^a offers resistance to the wheel to effect a pulling on the linkage that moves the valve arm 51^a. Movement of this arm will rotate the valve block to the point where the channels register with the ports connecting pipe 24 with pipe 34, and pipe 26 with pipe 30 corresponding to that shown in Fig. 7. The subsequent striking of the wheel on the rocker arm 53^a will actuate the pump piston 56^a to cause the operating medium to flow from the storage tank 32 through the pump 36 from which it passes through the valve 28 into the pipe line 24

leading to the top of the gate operating cylinder 13, and fluid entering through the port 17 will act on the teeter valve 21 to close the port 16 causing the piston 12 to be lowered in the cylinder to raise the gate arm 2 to its vertical open position as shown in Fig. 1. The fluid in the cylinder below the piston 12 will flow through the ports 18 and 19 back into the storage tanks since a downward pressure against the teeter valve 22 has the effect of maintaining it in its neutral position leaving both of the port openings unobstructed to the flow of the fluid.

A similar function or cycle of operation takes place when the train passes over the rails in the reverse directions in which case the valve regulating fingers described as rigid and actuated by the passing of the wheels over the rails in one direction will be broken by the passing of the wheels in opposite direction and the fingers that were collapsible in one direction will become rigid in the opposite direction so as to dispose the valve operating arm 51^a in the opposite direction to establish communication between the valve ports which connect the pressure pumps with the port in the side of the gate operating cylinder that will effect a lowering of the gate. Thus the track instruments are designed, and so connected with the regulating valves, as to effect the lowering of the gate arm for either direction of travel of railway vehicles passing the tracks in the region of the crossing. Either air, inert gas, water, oil, glycerine or other suitable fluids may be employed in the operation of this system and it is evident that various connections may be effected with the operating mechanism to operate signals such as lights or sound alarms in connection with the operation of the gate arms.

It is evident from the foregoing description of this invention that the automatic railway gate operating device herein described provides a simple and effective means for operating railway gates with absolute safety and in an economical manner. The maintenance and cost of the apparatus is relatively small on account of the simplicity of the operating mechanism which is possible with the utilization of the fluid pressure operating medium.

Although one of the embodiments of this invention has been herein described it will be obvious to those skilled in the art that various modifications may be made in the details of construction and in the arrangement of the several cooperating parts without departing from the principles herein set forth.

I claim:

1. An automatic railway-crossing gate comprising a vertically swinging gate arm, operating mechanism for said arm, a fluid pressure cylinder having a piston for actuating said operating mechanism, a fluid pres-

sure pump communicating with said gate operating cylinder, a storage tank for maintaining a supply of the operating medium, a valve communicating with said cylinder, 5 pump, and tank to regulate the flow of the operating medium from the pump to the operating cylinder and from the latter to the tank and track instruments operating said pump and regulating said valve, said track 10 instruments, pump and valves being remote from the gate.

2. An automatic railway-crossing gate comprising a vertically swinging gate arm, operating mechanism for said arm, a pressure cylinder having a piston connected to 15 and for actuating said mechanism, a plurality of pumps in spaced relation and remote from said gate, storage tanks containing an operating medium, valves communicating 20 with said cylinder, pumps and tanks, and track instruments actuated by the wheels of railway vehicles passing over them to respectively operate and regulate said pumps and valves, said valves being connected by 25 pipe lines to the top and bottom of said cylinder and to said pumps and tanks.

3. An automatic railway-crossing gate comprising a vertically swinging gate arm, operating mechanism for said arm, a pressure cylinder having a piston connected to 30 and for actuating said mechanism, a pair of pumps spaced one on each side of said cylinder, a valve for each pump, a storage tank communicating with each pump and valve 35 and said cylinder, and track instruments for actuating said pumps and for regulating said valves, one of each of said pumps, valves, tanks and track instruments being arranged in groups to constitute an operating system 40 to raise or lower said gate arm, and two of such groups or systems being in spaced apart relation remote from said gate operating cylinder.

4. An automatic railway-crossing gate comprising a vertically swinging gate arm, operating mechanism for said arm, a pressure cylinder having a piston connected to 45 and for actuating said mechanism, a pair of pumps for exerting pressure on the piston operating medium, valves for directing the medium to either the upper or lower side of said piston, and track instruments for actuating said pumps and for regulating said valves, said instruments being operative for 50 either direction of travel of the vehicles passing over the tracks.

5. An automatic railway-crossing gate comprising a vertically swinging gate arm, operating mechanism for said arm, a pressure cylinder having a piston connected to 60 and for actuating said mechanism, two groups of pumps, valves and track instruments for conducting an operating medium to either the upper or lower side of said piston to raise or lower said gate arm, said

groups being in spaced relation on each side of said gate and adapted to alternately raise and lower said gate arm for one direction of travel of a train over the track.

6. An automatic railway crossing gate 70 comprising a vertically swinging gate arm, operating mechanism for said arm, a pressure cylinder having a piston connected to and for actuating said mechanism, a pair of pumps for exerting pressure on the piston operating medium, valves for directing the medium to either the upper or lower side of said piston, and track instruments for actuating said pumps and for regulating said valves, said valves comprising a stationary 75 housing having ports communicating with said pump, the upper and lower side of the gate arm operating piston, and a storage tank, and a rotatable cylinder actuated by the track instruments to establish communication between said ports.

7. An automatic railway crossing gate comprising in combination a vertically swinging gate arm, a fluid pressure actuating mechanism for said arm, and means operative through trains passing over the tracks in the region of the crossing and remote from said gate arm for controlling said actuating mechanism, said actuating mechanism comprising a fluid pressure actuated piston and cylinder embodying teeter valves for directing the operating fluid to raise or lower said gate arm.

8. An automatic railway crossing gate 100 comprising in combination a vertically swinging gate arm, a fluid pressure actuating mechanism for said arm, means operative through trains passing over the tracks in the region of the crossing and remote from said gate arm for controlling said actuating mechanism, said actuating mechanism comprising a fluid pressure actuated piston and cylinder embodying teeter valves for directing the operating fluid to raise or lower said gate arm, and said control means 105 comprising a regulating valve for directing the operating fluid from a source of pressure to said cylinder and back to a storage tank, and from said tank to said pressure source.

9. An automatic railway crossing gate comprising in combination a vertically swinging gate arm, a fluid pressure actuating mechanism for said arm, and means operative through trains passing over the tracks in the region of the crossing and remote from said gate arm for controlling said actuating mechanism, said means for controlling the actuating mechanism comprising a pressure pump, actuating mechanism for said pump and a regulating valve for directing the operating fluid from said pump to said cylinder.

10. An automatic railway crossing gate 130 comprising in combination a vertically

swinging gate arm, a fluid pressure actuating mechanism for said arm, and means operative through trains passing over the tracks in the region of the crossing and remote from said gate arm for controlling said actuating mechanism, said means for controlling the actuating mechanism comprising

a pressure pump, actuating mechanism for said pump and a regulating valve comprising a rotatable valve having a plurality of 10 ports adapted to communicate with said cylinder.

In testimony whereof, I sign my name.

THOMAS N. COFFELDER.
